UNITED STATES PATENT OFFICE

HERBERT S. SNEAD, OF MONTCLAIR, NEW JERSEY, ASSIGNOR TO OTIS ELEVATOR COMPANY, OF JERSEY CITY, NEW JERSEY, A CORPORATION OF NEW JERSEY.

SAFETY DEVICE FOR ELEVATOR CARS.

Application filed January 12, 1922. Serial No. 528,590.

To all whom it may concern:

Be it known that I, HERBERT S. SNEAD, a citizen of the United States, residing at Montclair, in the county of Essex and State of New Jersey, have invented a new and useful Improvement in Safety Devices for Elevator Cars, of which the following is a specification.

My invention relates to improvements in safety devices for elevators, more particularly to safety devices for that class of elevators which is provided with door-actuated control mechanism, which involves a switch in the control or operating circuit to the hoisting motor controlled by the position of the car gate or door. An object of my invention is to provide appliances or means on both the hatchway door and the elevator car gate which will interfere with each other in the closing of the car gate, and obstruct or prevent the closing of the elevator car gate and the switch unless the hatchway door is closed in advance of the closing of the elevator car gate.

I obtain another object by the appliances or means on the elevator car gate, the said appliances or means being a part of my present invention, and comprises a member flexible in one direction only, called later on in the specification a cam, whereas when the elevator car or car gate becomes out of true with the elevator well room or hatchway through a displacement of the elevator car guide shoes or guide rails, or any other reason, and the displacement results in bringing the elevator car or its gate nearer to the hatchway openings or floor landings than is normal, the said flexible member of the appliances or means of my invention on the elevator car gate will strike the sills of the floor landings or other projections that are in its path of travel throughout the elevator hatchway in the up-and-down travel of the elevator car when the said displacement occurs, which indicates that the elevator car or its gate is out of true with the hatchway in which it travels, since the said member of the appliances on the elevator car gate is flexible in a direction to adapt it to give way when it strikes a floor landing sill, or other projections that are in its path of travel, the elevator car gate will not be torn off the elevator car as might be the case if the member was rigid, but in the case of my present invention, the flexible member is

adapted to be torn off the elevator car gate, but, only when the displacement of the elevator car guide shoes or guide rails, or for any other reason, resulting in a displacement of the elevator car, so to speak, has reached great proportions.

I attain the above objects by the mechanism illustrated in the accompanying drawings.

Other objects of the invention will appear hereinafter.

Figure 1 illustrates somewhat diagrammatically a typical car switch controlled elevator, embodying my invention.

Figure 2 illustrates a fragmentary part of an elevator car collapsible or folding gate, and guide rail for same, with a part of my invention attached thereto, together with a fragmentary part of a hatchway floor landing door with the other part of my invention attached thereto.

Figure 3 is a vertical view of Figure 2.

Figure 4 is a vertical view in section on the line 4—4, Figure 2.

Figure 5 is a plan view of Figure 2.

Similar numerals refer to similar parts throughout the several views.

Referring now to Figure 1, an elevator car, C, is suspended by hoisting cables, 1, which run over a driving sheave, 2, secured to a shaft, 3, of a motor, M. The usual counterweight, cwt., is secured to the ends of the cables opposite to the car.

Electromagnetically operated reversing switches to control the motor, M, are designated, R and R'; the switch R controls the motor for descending direction of car travel, and the switch R' for ascending direction of travel. Operating means for operating the reversing switches R and R' is designated B. A main line switch is designated by the letter A.

An electrical contact, consisting of a copper segment D, is insulated from, but mounted on the elevator car gate I, and another electrical contact E is mounted on the side of the elevator car C. These contacts are brought together in contact with each other when the car gate I is closed. The contacts are in an electrical control or operating circuit to the hoisting motor M. When the contacts are closed against each other the control circuit for the hoisting motor M can be closed by operating the operating means B in a direction either to the left or right.

depending upon which direction of car travel is wanted. When the contacts are separated from each other, the control circuit for the hoisting motor cannot be closed, and, consequently, the elevator car C cannot be started away from a landing. I have shown the contacts mounted on the elevator car gate I and another part of the elevator car C, but it is to be understood that they can be mounted 10 on any other part of the elevator car C or parts affixed to the car, provided that they function to close or open the control or operating circuit to the hoisting motor M, as the case may be when the elevator car gate I is closed or opened respectively.

In the Figure 1 a control circuit for operating the hoisting motor M, is from main a, through the left hand blade of the main line switch A, by wire 4, contact 5 of the reversing switch R', by wire 6, through winding 7 of the reversing switch R', assuming that an up direction of travel of the elevator car C is wanted, by wire 8, contact 9, and lever 10 of the car switch D, assuming 25 the contact and lever to be contacting each other, by wire 11, contact E on the elevator car, contact D on the elevator car gate, back to contact E, assuming that the contacts are closed against each other, by wire 12, 30 through the middle blade of the main line switch A, to the main b. The reversing switch R' will close its contacts as a result of the circuit through its winding 7, just traced, and through its now closed contacts, 35 circuits are established for operating the hoisting motor M, which will rotate in a direction to cause the elevator car C to travel in an ascending direction. For a descending direction of elevator car C travel, the reversing switch R would be caused to be operated. The parts mentioned and their arrangement 40 as shown are old, and need not therefore be further described.

In my invention I have used a cam F, 45 which I will describe fully hereinafter, which may be affixed to the elevator car gate, I, in any manner that may be deemed desirable, and is carried on the gate guide rail 19, and moved in the operation of opening and closing the elevator car gate. In 50 combination with the cam F, I have employed another cam G, which is fastened to an angle, H, and it in turn fastened to the body of the hatchway door J, or inserted 55 therein as may be deemed desirable, and so mounted that it will engage or contact with the cam, F, on the elevator car gate rail 19 when the two cams F and G are brought together in the operation of closing the elevator car gate. The two cams F and G in 60 contact with each other, constitute an obstruction to the closing of the car gate, I, until after the hatchway door J is first closed. In Figure 1 the position of the 65 cam G differs somewhat from its position

in the other figures that it appears in, for the reason to make it stand out more clearly in the figure, than it would if shown as in the other figures that it appears in; however, either position of the cam G may be 70 found to be correct for actual use.

Referring to Figures 2 to 5 inclusive, the part of my invention carried on the elevator car gate rail 19 comprises a carrying member 13, secured within a pipe or tube 14, by screws 15. The pipe or tube 14 is slotted throughout a short part of its length and is riveted, or as I have shown for convenience, fastened to the folding or collapsible elevator car gate, I, by strips 80 16, fastened to the gate and pipe. The carrying member 13, solid at its top center part only, and slotted through its remaining part, extends outwardly in opposite directions, narrowing down to the point where it enters 85 the pipe 14. Within the slot formed in the carrying member 13 are rollers 17, held by pins 18, in the member 13 which together with the slot in the pipe 14 encompasses the car gate guide rail 19, upon the top side of 90 which the top rollers 17 travel, and on the bottom or under side of the rail the bottom roller 17 travels. A three point suspension is obtained by the present arrangement of rollers 17, which adds materially to the 95 strength and stability of the elevator car gate, and is a means of support for the cam F; also, the present arrangement of rollers 17 is entirely independent of the construction of the elevator car gate and of 100 whatever means of fastening to the car gate that may be employed. The construction is such that the cam F will resist a torsional displacement in a plane parallel with the car gate track 19, regardless of the lack of 105 rigidity of the car gate, I. Upon the front side of the carrying member 13 are formed hinges 20, which hold the cam F by means 110 of a pin 21. Also upon the front side of the member 13, are formed projections 22 between which the cam F hangs, their object being to steady the cam F, and to guard 115 against any side play that the cam may develop and transmit any torsional strains through the carrying member 13, and the rollers 17, to the elevator car gate track 19. The cam F of the part of my invention carried on the elevator car gate track 19 is adapted to be moved in a plane, perpendicular to the car gate track, against the action 120 of a spring, 23, which tends to hold the cam F, in its out position, so to speak, a finger 24 formed at the top of the cam F, limits the action of the spring 23 and fixes the out 125 position of the cam F. A cup or recess 25 is formed in both the cam F and the member 13, for the ends of the spring 23 to lie in. In an up direction of travel of the elevator car C, should the cam F strike a floor landing sill, or any other projection in the hatch- 130

way that is in the path of the cam F, the cam will cam off the sill or other projection by its surface 26, and in a downward direction of travel of the elevator car, the cam F will 5 cam off by its surface 27. Hereinbefore I said that the cam F would be broken off should the displacement of the elevator car reach great proportions. This would occur in a down direction of travel of the elevator car 10 C, whereas when the cam F struck the floor landing sill or other projection at its end 28, the cam F might be caused to be moved straight up and not cam in toward the gate track 19, as it would ordinarily do, but in the 15 event of the cam F striking as just told, the pin 21 will be broken off, as it is small and fragile enough to take care of the above emergency. The elevator car C traveling in an up direction of car travel when the elevator 20 car is in an extreme displaced position, so to speak, the cam F, in striking a floor landing sill at this time after camming off the floor landing sill by its surface 26, will push the car gate further into the elevator 25 car.

In Figure 2, it will be seen that the cam F on the elevator car gate I, has other camming surfaces 29 and 30, they being adapted in the up or down travel of the elevator car 20 C, when the cam F is in line with the cam G on a floor landing door J, due to the door being partly opened, to strike the curved ends 31 or 32 respectively of the cam G. The surface 29 or 30 of the cam F on the 25 elevator car gate will cam the cam G on the floor landing door J, to one side in the above instance, the camming action being in the direction that the door J is moved to be closed, so that when the above camming 30 takes place the door will be caused to be moved to be closed, but if the elevator car gate I is inclined to be moved easier than the floor landing door J, when the cams F and G contact with each other, the car gate 35 will be opened, breaking the engagement of the contact D with the contact E, which will cause the elevator car to be stopped in its travel. It will be understood that my invention of a safety device for elevators is 40 adapted to be used with automatic door closers of either hand or power type and that when the floor landing door has been closed it is normally locked against being opened until the elevator car has again arrived at the landing at which the door is at, 45 but it may be the case that the door did not lock itself and that, while the elevator car was at some other point in its travel, the door may have been opened to a degree that 50 the cam G on the door has been brought in line with the cam F on the elevator car gate, told above, and that in the travel of the elevator car it passes the floor landing at which the opened door is, at which time the cam 55 F on the elevator car gate will strike the

cam G on the floor landing door by its surface 29 or 30, depending on the direction of travel of the elevator car and cause the opened door, to be moved to be closed or the car gate to be opened, as told above. 70

I will now proceed to describe the closing of the elevator car gate, assuming that the floor landing door has to be closed in advance of closing the elevator car gate and after which the elevator car can be started 75 away from the landing. The car being at a landing, and the floor landing door thereat being opened, and the elevator car gate being opened, and it being desired to start the car away from the landing, the floor 80 landing door will have to be closed first, because the control circuit to the hoisting motor M will have to be closed by the contact D and E, before the elevator car can be started, and therefore, until they are first 85 brought into contact with each other, the control circuit will not be established. They cannot be brought into contact with each other without closing the elevator car gate I, and the latter cannot be closed without first closing the floor landing door J, 90 and thereby move the cam G, affixed to it, out of the path of the cam F in the closing movement of the elevator car gate F. Thus it will be seen that the floor landing door J 95 will have to be closed first, before the contacts D and E can be closed together by the closing of the elevator car gate I. The arrangement of the cams F and G is such that they are in a path with each other in the 100 closing movement of closing the elevator car gate I despite the compression or, in the absence of the spring 23, further, the means of support and attachment of the cam F on the car gate and its carrying member 13, 105 and of the cam G, and its fastening H on the floor landing door are sufficiently rigid so that the cam F cannot be forced past the cam G, in the closing movement of closing the floor landing door. The floor landing door J being closed, and the elevator car gate I now being closed, and the contacts D and E now being together, the control circuit for operating the hoisting motor M to 110 operate the elevator car C, can now be closed by operating the operating means B, as shown hereinbefore. In this way, I virtually assure that the door J at a floor landing will be closed, and not left open, upon the car moving away from the landing. 115

I wish it to be understood that my invention is not limited to the details or construction or arrangement of parts herein disclosed, and that various modifications might be made within the spirit and scope 120 of my invention. 125

What I claim is:

1. In an elevator the combination of the car, the car gate, a guide rail for the gate at its top, a slotted member carried astride 130

- of, and adapted to travel on the said rail, and a slotted pipe to which the said member is secured, and affixed to the car gate, the said rail being within the slot in the pipe 5 also, the whole to resist a torsional displacement of the car gate in a plane parallel with the guide rail for the car gate.
2. In an elevator the combination of the elevator car, a cam thereon, a car gate, the 10 cam being affixed to the car gate, a guide rail, the gate and cam being carried on the rail, a shaft door and a cam thereon, the latter serving to act as an obstruction to the cam on the car to prevent the closing of the 15 car gate without first closing the shaft door.
3. In an elevator the combination of the elevator car, a cam thereon, a guide rail for the same, the cam being carried on the guide rail by a three point suspension member, a 20 shaft door and a cam thereon, the latter serving to act as an obstruction to the cam on the car to assure the closing of the shaft door.
4. In an elevator the combination of the 25 elevator car, a cam thereon, a car gate, the cam being affixed to the car gate, a guide rail for the cam, which is carried on the rail by a three point suspension member, comprising three rollers and their holding members, a shaft door and a cam thereon, the latter serving to act as an obstruction to the 30 cam on the car to prevent the closing of the car gate without first closing the shaft door.
5. In an elevator the combination of an 35 elevator car, a cam having two camming surfaces and flexible in one direction and rigid in the other direction, and adapted in the travel of the elevator car, when the gate happens to be displaced, to strike the sills 40 of the floor landings or other parts projecting out in its path by either of its camming surfaces and cam the gate into its normal placement, and a guide rail adapted to carry the cam.
- 45 6. In an elevator the combination of an elevator car, a car gate, a cam on the car and affixed to the car gate, the cam having two camming surfaces and flexible in one direction and rigid in its other direction, 50 and adapted in the travel of the elevator car, when the gate happens to be displaced, to strike the sills of the floor landings or other parts projecting out in its path by either of
- its camming surfaces and cam the gate into its normal placement, and a guide rail 55 adapted to carry the cam.
7. In an elevator the combination of the elevator car, a cam on the car having two camming surfaces, a shaft door and a cam thereon, the cam on the car adapted to 60 strike by either of its camming surfaces, in the travel of the car, the cam on the shaft door and cam the door closed.
8. In an elevator the combination of the elevator car, a car gate, a cam on the car 65 affixed to the car gate and having two camming surfaces, a shaft door and a cam thereon, the cam on the car adapted to strike by either of its camming surfaces, in the travel 70 of the car, the cam on the shaft door and cam the door closed.
9. In an elevator the combination of the elevator car, an electric hoisting motor, a car gate, a cam on the car affixed to the car gate 75 and having two camming surfaces, a shaft door and a cam thereon, an electrical switch mounted on the car and in the controlling circuit of the motor, adapted to be closed by the car gate when closed, the cam on the car adapted to strike by either of its camming surfaces, in the travel of the car, the cam on the shaft door and result in camming the car gate open and the opening of the switch on the car to stop the car.
10. In an elevator the combination of an 80 elevator car, and a car gate, a safety device, comprising a carrying member and a cam affixed thereto, being suspended by a pin between hinges formed on the carrying member, and held out from the face of the carrying member by a spring held in pockets 85 formed in the cam and carrying member.
11. In an elevator the combination of an 90 elevator car and a car gate, a safety device, comprising a carrying member and a cam 95 affixed thereto, being suspended by a pin between hinges formed on the face of the carrying member, a spring held between the cam and carrying member to give the cam flexibility in one direction and stops 100 or projections formed on the face of the carrying member to hold the cam rigid in its other direction.

In testimony whereof, I have signed my name to this specification.

HERBERT S. SNEAD.
